JOSEPH EDOUARD LUCIEN PELLETIER AND GASTON FERNAND MONIER,
OF PARIS, FRANCE.

DUMB-BELL.

No. 850,964.

Specification of Letters Patent.

Patented April 23, 1907.

Application filed September 22, 1906. Serial No. 335,760.

To all whom it may concern:

Be it known that we, JOSEPH EDOUARD LUCIEN PELLETIER and GASTON FERNAND MONIER, citizens of the Republic of France, 5 both residing at No. 40 Avenue Malakoff, Paris, in the Department of Seine, France, have invented a new and useful Improvement in Dumb-Bells, of which the following is a specification.

10 The present invention relates to improvements in the construction of dumb-bells of variable weight—that is to say, of dumb-bells having hollow ends for the purpose of receiving supplementary movable weights 15 which can be introduced or withdrawn at will.

The improvements relate to the means adopted for putting the movable weights into the hollow chambers of the balls of the dumb-bell; further, to the means for locking or retaining in position the movable weights thus introduced, and, finally, in means for causing automatically the removal of the movable weights under the action of a spring placed in the dumb-bell.

25 The invention is illustrated in the accompanying drawings, in which—

Figure 1 shows a longitudinal section of a dumb-bell constructed according to this invention. Fig. 2 shows an end view of the 30 ball A of the dumb-bell shown in Fig. 1, the movable weight appearing being represented as locked or in position of engagement in the weighted chamber. Fig. 3 shows an end view of the ball A of the dumb-bell shown in

35 Fig. 1, the movable weight being represented in the position which permits it to enter freely or to be removed automatically from the weight-chamber. Figs. 4 and 5 show, respectively, an elevation and a diametrical 40 section of a movable weight for the dumb-bell shown in Fig. 1. Fig. 6 is a longitudinal elevation and partial section of a constructional modification of a dumb-bell containing the object of the invention. Fig. 7 is an end 45 view of the dumb-bell shown in Fig. 6; Figs. 8 and 9, elevation and diametrical section of a movable weight for the dumb-bell shown in Fig. 6.

50 The dumb-bell illustrated in Figs. 1 to 6 comprises two balls of spherical parts A A', united by a hollow bar B. The balls A A' are hollowed out along the axis of the dumb-bell, so as to form two cylindrical chambers C C',

which communicate by means of the hollow in the bar B. These chambers C C' are 55 adapted to contain supplementary movable weights E E'. These weights, of suitable thickness, according to the number which are to be placed in each chamber, have the form of a portion of a hollow sphere, of which the 60 external curvature corresponds to that of the sphere of the balls A A'. These weights E E' have their two faces (concave and convex) parallel, so that they can be placed one upon another and form a cylindrical mass which 65 fills the interior of the chambers C C' and corresponds to the sphericity of the balls A A'. Upon the open orifice of each chamber C C' there are formed in the casting two little lugs D D' (D' D'), projecting toward the interior and diametrically opposed to one another. The weights E E' are provided with notches F F' (F' F''), corresponding to the 70 projections of the lugs. They have also grooves G G' (G' G'') for bolting to engage 75 them with the lugs D D'. A spiral spring H, placed in the hollow handle B, presses up its ends upon the first weights L L', placed in the chamber C C', but which is prevented from escaping by means of a pin M M', projecting in each of its slots. The weights L L' are thus held permanently in the chambers C C', so as to mask the opening of these 80 chambers when the movable weights E E' have all been withdrawn.

85 In order to facilitate their correct placing in the chambers C C', the weights L L' are provided with a tubular projection N N', which surrounds the spring and slides freely in the hollow handle-bar B. The same result might be obtained by adapting to the weights L L' a solid handle or stem instead of the tubular projections N N'. In this case 90 the spring H would surround the said bars, leaving space for free motion in the handle-bar B. According to this arrangement it will readily be understood that in order to introduce a movable weight E into the chamber C, for instance, it suffices to place this weight at the entrance of the chamber, causing its notches F to coincide with the lugs D at the entrance, Fig. 3, and then to push it into the chamber, compressing the spring H, and finally to rotate it a quarter of a turn to bring its locking-grooves G into engagement 105 with the projections D, Fig. 2. The spring

H by reason of its internal pressure tends to force the weight outward and insures the firmness of the lock.

In order to withdraw a movable weight E from the chamber F, for instance, the opposite operation is performed—namely, pressure is applied upon the movable weight sufficient to compress the spring H and disengage the grooves G from the projections D; then the weight is rotated a quarter of a turn, so as to bring the notches F opposite the lugs D. If then the spring H be allowed to extend freely, the movable weight, which is visible, is thrown outward and the weight which follows it immediately in the chamber takes its place and locks with the projections.

In order to facilitate the rotation of the movable weights, their front face is provided at the middle with a rectilinear slot O to receive a turn-screw or simply a coin which serves to rotate them.

The invention is the same whatsoever the outer form of the balls of the dumb-bell may be, as also the essential feature of the invention is retained if the dumb-bell is constructed with a solid handle.

Figs. 6 to 9 illustrate by way of modification of the construction a dumb-bell of which the weights a a' are of cylindrical form and the handle b is solid. Each end of the dumb-bell is hollowed out to form a cylindrical weight-chamber c. The weights are formed of flat plates e, provided with notches f and locking-grooves g in order to engage with the lugs d, projecting at the entrance of the weight-chamber. The spring h pressing upon the bottom of the weight-chamber in-

sures at will the locking of the parts g of the weight with the lugs d or the automatic discharge of the weights when the notches f, with which it is provided, are brought over against the lugs d. The number, the form, and the arrangement of the holding-lugs at the entrance of the weight-chamber may be varied if care be taken to provide the movable weights with a suitable number of slots and of grooves of the requisite shape.

What we claim is—

1. In a dumb-bell of the type set forth, hollow chambers having insertion-orifices, projections on the rims of said orifices removable weights adapted to fit within said chambers, recesses on said weights adapted to permit the weight to pass the said projections, and a spring in the handle adapted to press the weight next to the orifice and prevent its turning into the releasing position.

2. In a dumb-bell of the type set forth, hollow weight-chambers, the weights L L' in said chambers, a spring in contact with said weights, the recesses F F' on said weights, the stopping-pin M M' in said dumb-bell, and the guiding-bar N N' connected to said pin adapted to coöperate with the spring and prevent the escape of the weights.

In testimony whereof we have signed our names to this specification in the presence of subscribing witnesses.

JOSEPH EDOUARD LUCIEN PELLETIER.
GASTON FERNAND MONIER.
